UNITED STATES PATENT OFFICE.

WILLIAM SEEDHOUSE, OF SHEFFIELD, ENGLAND, ASSIGNOR TO ROBERT SORBY & SONS, LIMITED, OF SHEFFIELD, ENGLAND.

SHEEP-SHEARS.

No. 797,233.

Specification of Letters Patent.

Patented Aug. 15, 1905.

Application filed February 21, 1905. Serial No. 246,773.

To all whom it may concern:

Be it known that I, WILLIAM SEEDHOUSE, a subject of the King of Great Britain and Ireland, residing at Clarodon Works, Charlotte street, Sheffield, county of York, England, have invented a certain new and useful Improvement in Sheep-Shears, (for which I have applied for Letters Patent in Great Britain, No. 10,729, dated the 10th day of May, 1904,) of which the following is a specification.

This invention relates to an improved method of constructing sheep-shears having detachable blades, the object being to simplify the manufacture by dispensing with all loose parts—such as screws, wedges, and the like—and to make the various parts interchangeable, and in order that my invention may be clearly understood and dissociated from other methods of construction having the same object in view I have illustrated the invention in the annexed sheet of drawings, to which reference will be made.

Figure 1 represents a sheep-shear made according to my invention; Fig. 2, enlarged view of the nozzle formed upon each shank; Fig. 3, enlarged view of the butt-end of blade with its tang.

In carrying out the invention I punch or otherwise cut out from flat steel blanks of the shape required to produce the blade A and its tang A² also other blanks to form the two shanks B and bow C in one piece, or separate shanks with a half-bow, which are afterward secured together, as may be preferred. The blades A are cut from steel of a quality suitable for carrying a cutting edge; the shanks B and bow C from spring-steel. The tang portion A² of the blade A is then bent round a mandrel to a tubular form, as shown in Fig. 3, but not to a complete circle. The extreme end forms an extension A³ of half a circle only to act as a stop. The tang is compressible in its diameter and has a resilient expandible re-

action. The end of each shank B is also bent round, producing an elastic expandible socket B² to receive the tang of the blade, and below the socket two lugs B³ are turned over and bent down toward each other, as shown in Fig. 2, to form a stop or abutment for the extension A³ to rest upon, and thus prevent any rotary action of the blade within the socket B², and also to determine the distance to which the shank of the blade shall enter the said socket by the end A⁴ of the part A² abutting against the edges of the lugs B. When the tangs of the blades are forced into the sockets of the bow-shanks, they will be firmly held therein by the grip or frictional contact of the slightly-expanded sockets upon the slightly-contracted blade-tangs, while the relative position of the cutting edges will be maintained by the extensions engaging with the flat surface of the lugs before mentioned.

What I consider to be novel, and desire to protect by Letters Patent of the United States, is—

1. In a sheep-shear having detachable blades, the bow-shanks having expandible tubular sockets and the blades having tubular tangs to fit the said sockets, radial lugs upon the shanks and coacting extensions on the blade-tangs as hereinbefore described and shown.

2. A sheep-shear having detachable blades A, provided with elastic compressible tubular tangs A², and semicircular extensions therefrom A³, the bow-shanks B, having elastic expandible sockets B², to receive said blade-tangs and provided with radial lugs B³, to engage with said extensions A³, as hereinbefore described and shown.

In witness whereof I have hereunto set my hand in presence of two witnesses.

WILLIAM SEEDHOUSE.
